TUBE HANGER

Filed Feb. 4, 1928

Inventor:

George W. Watts,
By J. W. Firth, Sub. Chrt. Reg. Niles,
Atty.

UNITED STATES PATENT OFFICE

GEORGE W. WATTS, OF WHITING, INDIANA, ASSIGNOR TO STANDARD OIL COMPANY,
OF WHITING, INDIANA, A CORPORATION OF INDIANA

TUBE HANGER

Application filed February 4, 1928. Serial No. 251,931.

This invention relates to improvements in tube hangers or supports. The invention will be fully disclosed in the following specification and accompanying drawings.

5 My improved tube hanger or support may be used, for example, for supporting the roof tubes in furnaces having flat suspended arches. For example, the improved device may support the roof tubes in an oil still.

10 In that form of device embodying the features of my invention shown in the accompanying drawings, Figure 1 is a view in side elevation, and Fig. 2 is a view taken as indicated by the line 2 of Fig. 1.

15 As shown in the drawings, 10 may indicate the flat suspended arch or roof of a furnace, for example, it may be the top or roof of the combustion chamber of an oil still. 11, 11 indicate the side walls of the furnace.

20 It frequently is necessary or desirable to support one or more rows of tubes, such as oil tubes, just below the roof of a furnace. For example, I have here shown two rows of oil tubes, the upper indicated by A and the lower by B. These tubes are here shown supported by my improved hangers. I preferably provide a set of hangers at each end of the tubes made of solid plates with holes provided to receive the ends of the tubes, and 25 use by improved hangers at one or more points intermediate the ends. Since the hangers are similar, I shall describe but one set.

25 Each hanger comprises a substantially rectangular plate or bracket 12 preferably cut out as indicated by 12^a and 12^b to save weight and material. The plate 12 is preferably of a width substantially equal to the width of one tube and one space between 30 tubes. The upper end of the plate 12 is provided with suitable holes 13 to receive supporting pins which may be the pins 14 extending through the channel members 15 above the roof 10.

35 The lower end of each plate 12 is provided with two outwardly facing aligned semi-circular tube supports 16. Below the semi-circular supports 16 is a centrally arranged circular tube support 17, here shown as carried 40 from the lower ends of the supports 16 by

means of the bars 18. The opposed faces of the semi-circular supports 16 are preferably joined by the bar or web 19 to add strength.

45 The plates are mounted in alignment, as shown in Fig. 2, so that the semi-circular supports 16 of adjacent plates co-operate to carry a single tube 20 of the row A. The circular supports 17 carry the tubes 21 of the row B.

50 While I have shown and described certain embodiments of my invention, it is to be understood that it is capable of many modifications. Changes, therefore, in the construction and arrangement may be made without departing from the spirit and scope 55 of the invention disclosed in the appended claims, in which it is my intention to claim all novelty in my invention as broadly as possible in view of the prior art.

55 What I claim is new, and desire to secure 60 by Letters Patent, is:

65 1. A furnace structure, including a plurality of rows of horizontal tubes; a support; and a plurality of tube holders depending from said support, each holder carrying one 70 tube of a horizontal row of tubes in one plane, and having parts co-operating with parts of adjacent holders arranged to carry the tubes of another horizontal row of tubes in another plane.

75 2. A furnace structure as claimed in claim 1 in which the tubes in one row are staggered with respect to those in the other.

80 3. A tube hanger for suspending a bank of tubes in a furnace, the tubes in one row of the bank being staggered with respect to the tubes in another row of the bank, comprising, a plurality of brackets, each bracket being provided with a plurality of corresponding tube engaging surfaces for supporting the 85 tubes in different horizontal planes and different vertical planes, each of said brackets having a vertically extending portion adapted to be secured to and to depend from a portion of the roof structure of the furnace, said 90 brackets, when secured to the roof structure and disposed in alignment with one another in substantially one plane transverse the axes of the tubes and in juxtaposition to one another, each supporting one tube independent- 95 100

ly of every other bracket in the same plane and another tube in cooperative conjunction with a contiguous bracket.

4. Means for suspending a bank of tubes in a furnace comprising, a plurality of brackets, each bracket being provided with a plurality of tube engaging surfaces for holding the tubes in different vertical and different horizontal planes, a furnace roof structure, and a support carried by said roof structure and supporting said brackets in substantially one plane parallel the direction of the width and length of the brackets, said brackets being disposed adjacent one another and one supporting surface of each bracket being complementary to an adjacent supporting surface on the adjacent bracket whereby the complementary tube-supporting surfaces on adjacent brackets will engage substantially opposite surfaces of the same tube for supporting the tube and holding it in place.

5. In combination with a furnace roof, a tube hanger for suspending a bank of tubes in the furnace and beneath the roof thereof, including a bracket comprising a portion of greater width and length than the thickness thereof secured to and depending from the roof of said furnace and having a tube receiving opening through it in the direction of its thickness for securing and supporting one tube, a tube disposed through said opening, the marginal edge of said bracket above said opening being recessed and adapted to receive a tube partially therein, a second bracket of substantially identical shape, conformation and function disposed adjacent the first said bracket and in the plane thereof and having a marginal recess complementary to the marginal recess of the first said bracket, and a tube disposed through said complementary recesses and supported by said brackets in conjunction with one another, said tubes being staggered with respect to one another.

6. A furnace structure, including a plurality of rows of horizontal tubes; a support; and a plurality of tube holders each depending from said support, one holder carrying one tube of a horizontal row of tubes in one plane and having parts co-operating with parts of an adjacent holder arranged to carry a tube of another horizontal row of tubes in another plane, said tube holder being in the form of a flat plate apertured in the direction of the axes of the tubes, the apertures permitting the passage of gases through the plates.

In witness whereof, I have hereunto set my hand this 1st day of February, 1928.

GEORGE W. WATTS.
